Primary Examiner — Joseph Kukella

Assistant Examiner — Darryl J Dardenne

(57) **CLAIM**

The ornamental design for a water jug, as shown and described.

DESCRIPTION

1. Water jug
  2. Water jug
  - 1.1 : Perspective
  - 1.2 : Perspective
  - 1.3 : Right
  - 1.4 : Left
  - 1.5 : Top
  - 1.6 : Bottom
  - 1.7 : Front
  - 1.8 : Back
  - 1.9 : Exploded
  - 2.1 : Perspective
  - 2.2 : Perspective
  - 2.3 : Right
  - 2.4 : Left
  - 2.5 : Top
  - 2.6 : Bottom
  - 2.7 : Front
  - 2.8 : Back
  - 2.9 : Exploded
- Water jug.
